RALPH C. STIEFEL, OF ELLWOOD CITY, PENNSYLVANIA.

TUBE EXPANDING AND SMOOTHING MILLS.

Application filed April 16, 1923. Serial No. 632,199.

To all whom it may concern:

Be it known that I, RALPH C. STIEFEL, a citizen of the United States, and a resident of Ellwood City, in the county of Lawrence and State of Pennsylvania, have invented a new and useful Improvement in Tube Expanding and Smoothing Mills, of which the following is a specification.

This invention relates to tube expanding and smoothing mills. The object is to provide a mill whereby tubes, particularly seamless tubes, can be expeditiously and in a single operation increased in diameter, rounded, the walls reduced in thickness and smoothed both inside and outside.

In the accompanying drawings Fig. 1 shows one form of mandrel and cooperating rolling bodies for attaining the object stated; and Figs. 2 and 3 illustrate modifications.

Diagonal or cross rolling mills for either piercing or expanding, or both, seamless tubes, are well known. Various forms and arrangements of rolling bodies for this purpose have heretofore been devised, and also various forms of mandrels have been employed in conjunction therewith. Such mills, with the use of conical skew rolls, or their equivalent, and in conjunction with a conical mandrel, have heretofore been proposed for expanding the tubes and reducing their wall thickness. With such mills as heretofore constructed, great difficulty was experienced to perform this operation because the pressure required to get the necessary bite on the tubular blank to force it through the rolls and over the mandrel has resulted in collapsing the tube or giving it such large ovality that it will no longer rotate, and will therefore stick in the rolls. Also with such mills it was experienced that if considerable wall reduction was effected it resulted in producing helicoidal grooves or scores on the interior of the tube which were carried to some extent to its exterior. By means of the mill herein illustrated and now to be described these difficulties are avoided and a tube with smooth inside and outside surfaces, of circular shape, and of very much greater diameter and with much thinner walls than the original tubular blank can be produced.

In Fig. 1 the rolling bodies are indicated at 4 and 5. These are shown as of short conical form, but if desired they may be

so-called disc rolls or any other suitable form. They are set with their axes at an angle, and askew, in order that in their rolling effect they not only produce a rotary movement of the blank passing through the same, but also a forward feed thereof, in a well known manner. These rolling bodies for their major portions 6 are of such conical form and their angularity is such as to produce a pass which diverges quite rapidly and widely from the entrance end towards the exit end of the pass. The forward portions 7 of the bodies are formed on a cone of greater angularity than their main body portions, giving a converging pass into which the tubular blank 8 is forced, by any suitable means such as by hand or an air or hydraulic pusher.

Lying in the pass of these rolling bodies is the one piece mandrel, which as is common, is free to rotate on the endwise immovable mandrel bar 9. The tip of this mandrel has a cylindrical portion 10 of considerable length, lying forward of the diverging pass proper. Its forward end will either be round, as shown, or tapered. This cylindrical portion serves to support the tubular blank on its interior at the entrance end of the pass and prevents it from collapsing and going oval to such an extent as to cause it to stick in the rolls. To the rear of this cylindrical tip portions is a conical portion 11, of an angularity greater than the angularity of the adjacent working faces of the rolling bodies 4 and 5, thus forming at this part a pass of decreasing dimensions wherein the tubular blank is reduced in wall thickness and expanded in diameter. As in all cross rolling operations, the reduction in wall thickness results in stretching the metal chiefly peripherally, thus increasing the diameter of the tubular blank, and said blank takes quite a decided oval form, being in contact with the mandrel portion 11 only in the plane of the pressure of the rolling bodies 4 and 5.

To the rear of the conical portion 11 is a second conical portion 12 which is of less angularity than the portion 11 and of substantially the same angularity as that of the adjacent working faces of the rolling bodies 4 and 5 so that the pass at this portion is of uniform dimensions. This portion of the pass serves to remove from the tube walls any helicoidal grooves or

corrugations which may be formed in the preceding part of the pass and gives the tube smooth surfaces both inside and outside. Also the tube walls are trued or equalized, that is, rendered of uniform thickness all around, and the ovality is reduced, that is to say, the tube is rounded. Consequently the tube leaving the rolls is smooth inside and outside, its walls are true, it is round, its diameter is much greater than that of the entering blank, and the thickness of its wall is correspondingly reduced.

The length as well as the ratio of length of the two conical portions 11 and 12 can be varied according to the diameter of the tube to be manufactured and the degree of wall reduction which it is desired to obtain. The length of the conical portion 12 should be as great as possible, and greater than the length of the conical portion 11. The cylindrical tip 10 of the mandrel renders it impossible to so crush or collapse the tubular blank as to prevent it from jamming or sticking in the rolls, that is to say, it serves to retain the blank sufficiently near a cylindrical form to enable it to rotate, notwithstanding that very heavy pressure is put upon it, as is necessary in order to start the blank to rotate and to feed it forward onto the conical portion 11 of the mandrel.

In the form shown in Fig. 2 the mandrel has only a single conical portion 14, whose angularity is the same as that formed by the diverging portion of the adjacent working faces of the rolling bodies. In this form the reduction in wall thickness takes place on the cylindrical tip portion 10 of the mandrel and to some extent at the beginning of the single cone 14, but the rear portion of this cone serves to smooth the tube walls inside and outside, equalize their thickness, and round the tube, as heretofore.

In both forms the mandrel is provided at its rear end with a cylindrical portion 15 which is generally provided with this type of mandrel.

The diameters of the rolling bodies increase in the same direction as the width of the pass increases and preferably in the same ratio in order to prevent twisting action on the blank.

The mill described enables a tubular blank to be rolled into a tube of much larger diameter and with much thinner walls than with prior mills and in a manner to prevent it from collapsing or taking on such ovality as will prevent it from rotating, and the tube produced is true, round, and smooth both inside and outside.

Various modifications may be made. For instance, in place of using a single reducing cone, as shown at 11 in Fig. 1, this opera-

tion may be effected by means of two or more cones acting successively. In that event the angularity of the reducing cones will progressively decrease from the first to the last, thus effecting the reducing operation in two or more successive steps, while still retaining the characteristics of the apparatus as heretofore described. For instance, as shown in Fig. 3, there are two reducing cones 11^a and 11^b, the latter being of less angularity than the former.

I claim:

1. In a tube expanding and smoothing mill, the combination with diagonal or skew rolling bodies disposed to form between them a pass the sides of which first converge and then diverge from the entrance end, of a one-piece mandrel located in said pass and having a substantially cylindrical forward portion serving to prevent collapse of the tubular blank under the grip of said rolling bodies as the tubular blank enters therebetween, and an adjacent conical portion increasing in diameter toward the exit end of the pass, the working frame of said mandrel and rolling bodies being so disposed that the walls of the blank at one portion of the pass are reduced in thickness and elongated peripherally and at another portion of the pass are equalized in thickness and the tube smoothed both inside and outside and rendered of circular form.

2. In a tube expanding and smoothing mill, the combination with diagonal or skew rolling bodies disposed to form between them a pass the sides of which first converge and then diverge from the entrance end, of a one-piece mandrel located in said pass and having a substantially cylindrical tip portion serving to prevent collapse of the tubular blank under the grip of said rolling bodies as the blank enters the pass, an adjacent conical portion increasing in diameter toward the exit end of the pass and serving with said rolling bodies to reduce the wall thickness of the blank and to stretch the same peripherally, and a succeeding conical portion also of increasing diameter toward the exit end of the pass and serving to smooth the tube inside and outside, equalize its wall thickness and render it of circular form.

3. In a tube expanding and smoothing mill, the combination with diagonal or skew rolling bodies disposed to form between them a pass the sides of which first converge and then diverge from the entrance end, of a mandrel located in said pass and having a substantially cylindrical tip portion serving to prevent collapse of the tubular blank under the grip of said rolling bodies as the blank enters the pass, a conical portion adjacent said cylindrical portion of greater angularity than the adja-

- cent working faces of the rolling bodies and serving with said rolling bodies to reduce the wall thickness of the blank and expand it, and a succeeding conical portion of the 5 same angularity as the adjacent working faces of the rolling bodies and serving with the said rolling bodies to smooth the tube walls inside and outside, equalize their thickness and render the tube circular.
- 10 4. In a tube expanding and smoothing mill, the combination with diagonal or skew rolling bodies, and a mandrel lying in the pass of said rolling bodies, said mandrel having a portion thereof disposed at such angular relation to the adjacent working 15 faces of the rolling bodies as to serve therewith to reduce the wall thickness of the tubular blank and elongate it peripherally, and having a succeeding conical portion of the same angularity as the adjacent working faces of the rolling bodies and serving therewith to render the tube circular, smooth the tube walls inside and outside, and equalize their thickness.

In testimony whereof, I sign my name.

RALPH C. STIEFEL.

Witness:

EDWIN O. JOHNS.
